UNITED STATES PATENT OFFICE.

GEORGE L. CROSMAN AND ARTHUR P. NASON, OF PORTLAND, MAINE, ASSIGNEES TO
G. A. CROSMAN & SONS CO., OF DEERING JUNCTION, PORTLAND, MAINE, A CORPORA-
TION OF MAINE.

SNOW SCOOP OR SHOVEL.

Application filed January 21, 1926. Serial No. 82,813.

Of the various devices for clearing snow falls by hand the so-called scoop has come to be one of the most popular by reason of its efficiency and its availability.

5 The greatest difficulty with the scoop has been its inability to withstand overstrain, or, in other words, its general design was such that over-zeal on the part of the worker or unusually adverse conditions in the snow to 10 be cleared, was apt to break or overstrain the device.

As a hand implement, its range of weight is limited so that increased strength can not be attained by mere structural augmentation.

15 To effect the necessary increase in strength, without increase in weight or cumbersomeness, we have devised our present invention.

The scoop shown in the accompanying drawings is a commercial embodiment of the 20 principles involved. To the characters indicating the several parts in the drawings reference is made in the accompanying specification. In the drawings:

Fig. 1 is a rear perspective view of such a 25 scoop.

Fig. 2 a front view of same, and

Fig. 3 a longitudinal section on the line 3—3 of Fig. 1.

The upwardly rising or angularly disposed handle of the scoop is the factor of its 30 characteristic ease in operation. However, it is also its element of strain and ultimate destruction in the ordinary course of use.

We, therefore, consider and treat our 35 handle as a part necessarily in bent lever relation to the runners 2. This will be discussed more in detail, but it will be understood that in the presence of crust or of heavy or compacted snow, deliberate or ac- 40 cidental increase of leverage creates a very severe strain at the apex of the angle (which generally is the fulcrum) of the leverage as a whole.

Considering now the runners 2, we pro- 45 vide these with angular ends 2' and forward prows 2².

At the prow ends we inset a cross bar 3 which extends transversely the full width of the scoop. The top of the cross bar 3 lies 50 flush with the top of the runners 2 to permit the bottom boards 4 to be laid close and drawn tight so as to avoid play while securing the maximum bracing effect. The lateral bottom boards 4' are extended beyond

the rear or beveled ends 2' of the runners to 55 form side supports for the handles 1.

The handles 1 are conveniently tapered at their upper ends and receive a cross bar 5 bolted thereon. At their lower ends the handles increase in thickness as at 1', and 60 meet at their bottom ends with the inclined ends 2' of the runners 2 so that they in fact project under the rear ends of the runners.

These angles of the bent levers formed by the runner and handles are reinforced by the 65 upturned rear ends of the runner-shoes 6, which are bolted through the widened portions 1' of the handles. The lower ends of the handles 1 are rounded in a continuous 70 curve from the undercut lower edges of the runners 2 up to the straight widened bearing 1' of the back of the handle. This gives an externally reinforced angle between runner and handle as well as a rounded completely 75 shod fulcrum for the scoop so that when the 80 scoop is reversed, it draws freely in flat or tilted position. It also aids in shaking back trimmings for a full load when clearing up.

Thus we see the runner and handles interlocked and externally braced and shod as 80 well as laterally supported by the rear ends of the boards 4'.

We may next consider the scoop back 7 which extends down to and in bearing upon the upper rear ends of the runners. This 85 affords the first cross lock for the inside angle of the leverage.

Next the central floor boards 4 are extended rearwardly across the lower edge of the back 7 and form an intermediate handle 90 spacing brace opposed to and in the plane of the extended ends of the outer boards 4¹.

The sides 8 extend from the rear ends of their lateral bottom boards 4¹ to the forward tip of the scoop where they have a forward 95 taper forming an inclined edge which is also outwardly beveled. These form side cutting edges which are shod with a strip of steel 8¹ folded and bent to protect the edge of the bevel and the corner of the scoop, 100 the bevel being filled at its juncture with the scoop bottom by a portion of the boards 4¹ or otherwise.

The forward ends of the runner shoes 6 are covered up and protected by a transverse 105 metal point 9 folded over and riveted at 9¹ to the front edge of the flooring 4 and affording with the metal shod beveled edges 8¹ a con-

tinuous cutting front to the scoop. Two of the rivets 9¹ pass through the runner and shoe ends. The top and bottom folds of the metallic sheathing 9 are of the same width 5 and the rivets 9¹ pass through both folds, as well as the included wood between said folds. This construction affords ample engaging surface for the rivets. The heads of the rivets are lodged in the upper fold of the 10 metal and thus have good anchorage.

The scoop may be operated as any ordinary scoop is now used, except that it may be worked harder and with greater efficiency and can be used to cut and break blocks or 15 crust and can be readily reversed to pull out a load.

The structural embodiments, details and combinations may be variously used and re-cast in variants of the form shown.

20 What we therefore claim and desire to secure by Letters Patent is:

1. In a snow scoop, a floor, a pair of runners beneath said floor and extending longitudinally the entire length thereof, the front 25 ends of said runners being formed as prows and merging with said floor, metal shoes on said runners, a folded metal strip covering the bottom edge of said floor and the ends of said prows and shoes, and means set 30 through said floor, said shoes, and said prows to hold the same in rigid relation to each other.

2. In a snow scoop comprising bottom and side walls, the forward ends of said walls being beveled, sheet metal guards on the 35 edges of said walls, a pair of runners, the front ends of said runners being formed as prows and merging with said bottom, a metal reinforcement covering the lower edge of said bottom and the included material 40 of said runners, said reinforcement on said bottom adjoining said metal guards on the edges of said side walls to present a continuous cutting edge, and means to maintain said parts and guards in rigid relation to 45 each other.

3. In a snow scoop, bottom and side walls, a pair of runners extending longitudinally the entire length of said bottom, a pair of handles contacting the upper ends of said 50 runners, runner shoes extending about said runners and handle juncture and fastened to said handle thereabout, the opposite end of said runners and shoes being extended as a prow and merging with said bottom, and a 55 folded sheet metal strip covering the lower edge of said bottom and said merging runners, and means passing therethrough to hold said bottom and said runners in rigid relation to each other.

60 In testimony whereof we affix our signatures.

GEORGE L. CROSMAN.
ARTHUR P. NASON.
